UNITED STATES PATENT OFFICE

JAMES ALAN RAE SMITH, OF MARPLE, ENGLAND

EXHAUST STEAM INJECTOR

Application filed May 22, 1930. Serial No. 454,751.

This invention relates to exhaust steam injectors, that is, to injectors in which part of the operative steam supply is at about atmospheric pressure. With such injectors it is necessary in order to obtain a sufficiently high delivery pressure, to effect delivery into a boiler such as that of a locomotive to supplement the exhaust steam with a supply of boiler or live steam which is usually introduced by means of a nozzle disposed concentrically within the nozzle through which the exhaust steam enters the injector.

The object of my present invention is to provide an improved construction of exhaust steam injector in which more effective utilization of the exhaust and live steam supplies is made resulting in the obtaining of a higher delivery pressure than is obtainable with present constructions or in economy of live steam consumption where a higher delivery pressure is not called for.

The invention comprises the improved construction of exhaust steam injector as hereinafter described and claimed.

Referring to the accompanying sheet of explanatory drawings:—

Figure 1 is a sectional elevation and Figure 2 a plan view partly in section of an exhaust steam injector constructed in accordance with my invention.

Figure 3 is a view similar to Figure 1 but showing a modified construction of injector.

a indicates the main exhaust steam inlet nozzle, *b* the water inlet space which is regulated by moving the nozzle *a* by means of the crank pin on the end of the spindle *c* relatively to the nozzle *d*. The water inlet branch is shown at *e*. Exhaust steam also passes by way of the passage *f* to the annular space between the nozzle *d* and the further nozzle *g*.

In accordance with my invention, the live steam which is to supplement the exhaust steam in raising the delivery pressure of the injector is admitted in the form of an annular jet around the end of the nozzle *g* and between the latter and the ordinary combining of mixing nozzle *h*. The live steam enters by the branch *i*. There is the usual delivery nozzle *j* and delivery valve *k*. The

combining nozzle *h* may have a flap as *m* or other means for providing a free escape from the combining nozzle when the injector is starting and before the water jet is established in the nozzle and a sufficient delivery pressure is obtained to effect delivery against the boiler pressure.

By arranging the live steam supply in the form of an annular jet beyond the water inlet space to the injector instead of through the exhaust steam and water inlet nozzles, I find that I obtain a much more efficient action due to less preliminary heating up of the exhaust steam and water and a more rapid condensation of the live steam which is in a thin large diameter annulus.

If desired, the second exhaust steam inlet *f* may be omitted, all the exhaust steam entering by the nozzle *a*. Or more than one annular exhaust steam inlet may be employed.

In Figure 3 there is arranged an annular space *o* between the exhaust steam inlet *f* and the live steam inlet *i* which is closed except for its annular communication with the mixed water and steam jet within. This closed annular space has been found to improve the efficiency of the injector. Figure 3 can also be taken as illustrating an injector in which two annular exhaust steam inlets are provided between the water inlet *b* and the live steam inlet *g*. In this case, of course, the space *o* will receive a supply of exhaust steam and will not be a closed space as above described.

What I claim is:—

1. In an exhaust steam injector, in combination, an exhaust steam inlet nozzle, and annular water inlet around the end of said nozzle, an annular live steam inlet around the mixed water and exhaust steam jet, a combining nozzle and a delivery nozzle.

2. In an exhaust steam injector as claimed in claim 1, means admitting exhaust steam in annular jet form between the water inlet and the live steam inlet.

3. In an exhaust steam injector as claimed in claim 1, means admitting exhaust steam in annular jet form between the water inlet and the live steam inlet and means providing an annular space open only to the mixed

water and exhaust steam jet between said annular exhaust steam inlet and said live steam inlet.

4. In an exhaust steam injector, in combination, an exhaust steam inlet nozzle, an annular water inlet around the end of said nozzle, a further nozzle forming a wall of said annular water inlet, an annular exhaust steam inlet around said further nozzle, an additional nozzle forming a wall of said annular exhaust steam inlet, an annular live steam inlet around said additional nozzle, a combining nozzle the inlet end of which forms a wall of said annular live steam inlet, and 15 a delivery nozzle.

In testimony whereof I have signed my name to this specification.

JAMES ALAN RAE SMITH.
